(57) CLAIM

The ornamental design for a bottle, as shown and described.

DESCRIPTION

FIG. 1 is a perspective view of the bottle of our design.

FIG. 2 is an elevation view thereof; and,

FIG. 3 is a top plan view thereof.

The broken line showing of a bottle neck is for illustrative purposes only and forms no part of the claimed design.

1 Claim, 3 Drawing Sheets

FIG. 3
